(57) **CLAIM**

The ornamental design for a combination switch for a motor vehicle, as shown and described.

DESCRIPTION

FIG. 1 is a front perspective view of a combination switch for a motor vehicle, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The lightened portions of the combination switch for a motor vehicle shown in FIGS. 1, 3, 4, and 7 are not part of the claimed design.
